HENRY A. WISE WOOD, OF NEW YORK, N. Y. ASSIGNOR TO CAMPBELL PRINTING PRESS & MANUFACTURING COMPANY, OF NEW YORK, N. Y. A CORPORATION OF NEW YORK.

STEREOTYPE-CASTING DEVICE.

982,225.

Specification of Letters Patent. Patented Aug. 24, 1909.

Application filed March 23, 1907. Serial No. 364,018.

To all whom it may concern:

Be it known that I, HENRY A. WISE WOOD, a citizen of the United States, residing at New York, in the county of New York and State of New York, have invented a new and useful Stereotype-Casting Device, of which the following is a specification.

Up to within recent years, the casting of stereotypes has been done in manually operated casting boxes which are necessarily manipulated at a very slow speed as compared with other printing operations and in fact, the delay occasioned in the production of stereotype plates has seriously interfered with the rapidity of printing in modern plants. In order to overcome this difficulty, I have heretofore invented several machines for the rapid production of stereotype printing plates but most of these have been suitable for use chiefly in large plants. Some attempts have been made also to provide means for operating stereotype molds in a comparatively simple way so as to increase the speed of the old printing plant without necessitating the use of complicated machinery, but such devices have usually been open to the objection that some complication was necessary in order to separate one part of the casting box from the other and from the plate and to remove one of the parts and the plate to a position in which the plate could be taken from the casting box.

The principal objects of the present invention are to provide means whereby the two parts of the casting box may be separated in a convenient and simple manner by a rocking motion without having any change in the character of motion of the part which carries the plate (said part being positively guided), without involving the use of complicated machinery suitable only for large plants, and at the same time, to provide means whereby the plate may be automatically separated from the casting box and delivered, preferably by gravity, in a convenient and simple manner into a position where it will be readily accessible and from which it may be removed at leisure; also to provide an efficient guiding device for the movable member of the box, a simple and effective clamping arrangement to secure the core in casting position so constructed that it can be employed to unlock the core and at the same time serve as a handle to separate the parts of the box, without necessitating the employment of two handles

for these two purposes or any unnecessary manipulation of the parts; to provide means for returning the devices for separating the plate from the box to normal position when the parts of the box are brought together; and generally, to improve and simplify the construction of casting devices of this general character.

Reference is to be had to the accompanying drawings which illustrate a preferred form of this invention and in which,

Figure 1 is a side elevation of a casting device constructed in accordance with this invention. Fig. 2 is a plan of the delivery frame which constitutes a part thereof. Fig. 3 is a side elevation of a portion of the device on an enlarged scale showing how the plate is delivered. Fig. 4 is a plan of the casting box proper, when in closed position. Fig. 5 is a front view of the same, and Fig. 6 is a sectional view of the bottom portion of the box with a portion of the core broken away.

The invention is shown as embodied in a device mounted on a base 10 having a track 11 thereon for supporting rollers 12 which carry the back or box member 13 of the casting device, which is usually called the drag. This part of the device is constructed in any desired way to secure a short reciprocatory motion of the back and for convenience it is illustrated herein as being operated in the same manner as the corresponding part of the casting box in my copending application for patent Serial No. 235,535, filed December 5, 1904.

The frame is accordingly shown as provided with a shaft 15 which has an operating handle 16. Secured to the shaft are pronged levers 17 which connect by links 18 with the back or drag 13 and form a toggle to operate the back and hold the same in closed position.

The back is shown as made hollow with suitable flexible inlet and outlet pipes 19 and 20 so that water may be circulated through the same to keep it cool during the casting operation. The back may be provided with any suitable form of matrix manipulating mechanism, which is not shown herein, as that shown in the above mentioned application is capable of use with this apparatus. The manner of manipulating the matrix and moving the back or drag may be changed within the scope of this invention in any desired way to secure the same results. It is

to be understood that the motion of the drag after the plate is cast is for the purpose of separating the same from the cast plate which is left on the core or cope. Consequently, this motion is of comparatively small extent, it being necessary merely to remove the drag far enough to permit manipulation of the core in a manner which will be described hereinafter.

- 18 After the plate is cast and the drag moved back, as is indicated in dotted lines in Fig. 1, the other mold member or core 60 is rocked directly forward, having a rocking motion from the start in order to deliver the cast plate. By reason of giving the back a motion to the rear before the core is rocked over, it will be seen that no complication in the motion of either part is necessary. The core can be given a simple rocking motion instead
- 19 of a combined sliding and rocking motion.

When the parts of the mold are in closed position ready for pouring, the core is locked to the frame or base 10 in the present instance, by a latch 21 pivoted on a fulcrum 25 stud 22 at the front of the core. This latch swings in a substantially vertical plane and engages a pair of studs 23 mounted on the frame on opposite sides of the front of the core. The latch is provided with a handle 24 for manipulating it. When the latch is swung to unlock the core from the frame, it will be seen that the handle will serve not only for this function, but for rocking the core over to the front and that a simple swinging motion of the latch by pulling the handle upwardly, is sufficient to accomplish both functions.

When the core is unlocked and swung to the front, it rocks on a pair of rockers 25 to which it is secured and which roll on tracks 26 formed on the frame or base. In order to cause the core to rock without sliding either forward or back along the tracks so that it may register with the back and with the delivery frame, as will be described, the rockers are provided with guides 27 which are engaged by rolls 28 on the frame. These guides are connected with the rockers in such a manner, and they are of such shape, that the rockers will be constrained to roll along the tracks and will be prevented from sliding upon them in either direction. For this reason, the shape of the guides 27 is substantially that of the cycloidal curve. As will be obvious, this form of guide serves to hold the rocker in proper position and to return the core to the same place after each operation.

The guides and the rockers are of sufficient length to permit the core to rock over 60 to a position beyond the horizontal so that when the core comes to rest, it is sufficiently inclined with its jet end down to permit the plate to be discharged by gravity. Consequently, if the casting position of the core is vertical, the effective rocking surface of the

rockers is more than 90 degrees and the guide is lengthened correspondingly.

In order that the cast plate may be separated from the core automatically when the core reaches such inclined position, the core 70 is provided with a pivoted arm 30 adapted to engage a stationary stop 31. This arm is provided with a cam surface 32 adapted to engage a roller 33 on a bell-crank 34 or the like which is connected to a link 35 bearing 75 on a movable mold wall 36 constituting the end segment of the casting box. This segment constitutes the bottom of the mold when the parts are in casting position, as is indicated in Fig. 6, and it is provided with 80 springs 37 secured to the core and on the segment itself to hold it yieldingly in proper position for forming the end of the cast plate. When the stop 31 is engaged by the arm 30 and the bell-crank 34 swung to the right, the 85 segment is forced outwardly from the cast plate so as to permit the plate to be removed from the core. At the same time an arm 40 connected with the arm 30 operates a link 41 which swings two or more arms 42 upwardly 90 into such position that anti-friction rolls 43 which they carry engage the edges of the plate and eject the same by lifting it to the position indicated in Fig. 3. As has been described, the core at this time is on an incline and as the rollers are now located in an inclined plane, it will be seen that the plate, being supported entirely by the rollers, is free to be delivered by gravity and that it will descend on a series of rollers 44 mounted on 95 the delivery frame 45 which is provided with a stop 46. The plate, therefore, is automatically delivered on the delivery frame and is left in a position from which it can be removed while the core is being returned to the 100 back for the production of another plate, if desired.

When the core is swung back, a roll 47 on a lever 48 connected with the link 41 engages a stationary cam 49 and returns the link and rollers to proper position out of the way of the plate so that the casting may be produced in the usual way. The side of the casting box which forms the edges of the plate which are destined to rest on the rollers 110 115 43, which constitutes a part of the matrix carrying mechanism, is not shown herein in detail as it can be constructed in any ordinary or desired manner. Such, for instance, as that shown in the above mentioned co- 120 pending application.

It is to be observed that the drag is located in position against the core by the toggle lever and that the core is locked to the frame by the latch which has been described. Consequently, the drag can be moved back out of engagement with the cast plate without unlocking the core and when this has been accomplished, the core can be unlocked and rocked forward with practically a single mo- 130

tion of the plate. At the end of the traverse of the core the ejection of the plate is accomplished automatically by the striking of the arm 30 against the stop 31. This not only releases the segment 36 from the casting and the casting from the core, but delivers the casting into an accessible position where it can be handled in any suitable way without further delaying the subsequent operation of the casting box to produce another plate.

It will be obvious, therefore, that a device constructed in accordance with this invention, is of a simple and inexpensive character so that it may be used in small plants and that it avoids the complication of a compound movement of a movable member of the casting box, permitting the two parts to move independently and providing for exact registration of the parts with each other upon their return motion; also providing for locking the rocking element of the box in a predetermined position, independently of the location of the other part of the casting box at that time.

While I have illustrated and described a particular form in which I at present prefer to embody my invention, I am aware that many modifications may be made therein without departing from the scope of the invention as expressed in the claims. Moreover, many features of this invention are useful in molds and machines for casting and molding other articles than stereotype plates. Therefore, I do not wish to be limited to the particular form shown but

What I do claim is:—

1. In a stereotype printing plate casting apparatus, the combination of an upright back and a core coöperating therewith mounted to turn to carry the cast plate from an upright position to a position where its edges are beneath.

2. In a curved stereotype printing plate casting apparatus, the combination of an upright back, a core coöperating therewith mounted to turn to carry the cast plate from an upright position to a position where its straight edges are beneath, and means engaging the straight edges of the plate.

3. In a curved stereotype printing plate casting apparatus, the combination of an upright back, a core coöperating therewith mounted to turn to carry the cast plate from an upright position to a position where its straight edges are beneath, and means for separating the plate and core.

4. In a curved stereotype printing plate casting apparatus, the combination of an upright back, a core coöperating therewith mounted to turn to carry the cast plate from an upright position to a position where its straight edges are beneath, and means engaging the straight edges of the plate and separating the same from the core.

5. In a curved stereotype printing plate casting apparatus, the combination of a back, a core coöperating therewith mounted to turn to carry the cast plate from an upright position to a position where its straight edges are beneath, and means engaging the straight edges of the plate on which the plate may be moved axially.

6. In a curved stereotype printing plate casting apparatus, the combination of an upright back, a core coöperating therewith mounted to turn to carry the cast plate from an upright position to a position where its straight edges are beneath, and means engaging the straight edges of the plate on which the plate may be moved axially.

7. In a curved stereotype printing plate casting apparatus, the combination of an upright back, a core coöperating therewith mounted to turn to carry the cast plate from an upright position to a position where its straight edges are beneath, and means engaging the straight edges of the plate and separating the plate and core on which the plate may be moved axially.

8. In a curved stereotype printing plate casting apparatus, the combination of an upright back, a core coöperating therewith mounted to turn to carry the cast plate from an upright position to a position where its straight edges are beneath, and means carried by the core for separating the plate and core.

9. In a curved stereotype printing plate casting apparatus, the combination of an upright back, a core coöperating therewith mounted to turn to carry the cast plate from an upright position to a position where its straight edges are beneath, and means carried by the core on which the plate may be moved.

10. In a curved stereotype printing plate casting apparatus, the combination of an upright back, a core coöperating therewith mounted to turn to carry the cast plate from an upright position to a position where its straight edges are beneath, and means carried by the core for separating the plate and core on which the plate may be moved.

11. In a curved stereotype printing plate casting apparatus, the combination of an upright back, a core coöperating therewith mounted to turn to carry the cast plate from an upright position to a position where its straight edges are beneath, and mechanism for locking the core and back.

12. In a curved stereotype printing plate casting apparatus, the combination of an upright back, a core coöperating therewith mounted to turn to carry the cast plate from an upright position to a position where its straight edges are beneath, locking mechanism for locking the core and back, and a handle for operating the locking mechanism and turning the core.

13. In a curved stereotype printing plate casting apparatus, the combination of an upright back, a core coöperating therewith mounted to turn to carry the cast plate from an upright position to a position where its straight edges are beneath, and a receiving device onto which the plate may be moved axially from the core.
14. In a curved stereotype printing plate casting apparatus, the combination of an upright back, a core coöperating therewith mounted to turn to carry the cast plate from an upright position to a position where its straight edges are beneath, ways, and a device onto which the plate may be moved from the core by means of said ways.
15. In a curved stereotype printing plate casting apparatus, the combination of an upright back, a core coöperating therewith mounted to turn to carry the cast plate from an upright position to a position where its straight edges are beneath, means for separating the plate and core on which the plate may be slid axially, and a device upon which the plate may be slid from its position over the core.
16. In a stereotype casting device, the combination of an upright rectilinearly movable back, and a core capable of being rocked.
17. In a stereotype casting device, the combination of a reciprocable back with a core capable of being rocked, and a guide for controlling the motion of the core.
18. In a stereotype casting device, the combination of a bodily movable casting box or back, a core therefor capable of being rocked, and means for constraining the core to rock throughout its entire traverse and for preventing its sliding during its traverse.
19. A stereotype casting device, comprising a rocking mold member, rockers connected therewith, a track supporting the rockers, and a cycloidal guide carried by the rockers.
20. A casting device, comprising a mold having a rocking mold member, and a cycloidal guide for preventing longitudinal motion of the rocking member.
21. A casting device, comprising a mold having a movable member, rockers connected with said movable member, and a cycloidal guide connected with the rocker, said rockers being of such length as to permit the movable member to rock from casting position into an inclined position.
22. A casting device comprising a substantially vertical movable mold member and means for turning said mold member into inclined position with its jet end down, whereby the casting may be delivered by gravity.
23. A casting device, comprising a movable mold member normally in substantially vertical position, rockers connected therewith, and a track for the rockers, said rockers and track being of such length as to permit the mold member to be rocked over into inclined position with its jet end down, whereby the casting may be delivered by gravity.
24. A casting device, comprising a movable mold member, rockers therefor, and a track for the rockers, said rockers having an extent of more than 90 degrees whereby the mold member may rock from vertical to an inclined position with the jet end thereof in a lower plane than the rest of the mold member.
25. In a casting device, the combination of a stationary frame, a horizontal track thereon, a pair of rockers on said track, a mold member supported by said rockers, said rockers constituting a segment of a circle of more than 90 degrees, a latch on the mold member adapted to engage the frame, said latch having a handle by which the latch may be unlocked and the mold member rocked into inclined position with its jet end down.
26. In a casting device, the combination of a frame having a track thereon, rockers mounted on said track, a mold member mounted on the rockers, a latch pivoted on the mold member on an axis at right angles to the surface of said mold member and adapted to engage said frame to lock said mold member thereto, said latch having a handle for unlocking it and for rocking the mold member.
27. In a stereotype casting device, the combination of a frame, a substantially vertical movable back, a movable core coöperating therewith, means for locking the core to the frame in a substantially vertical position, and means for moving the back against the core and locking it in such position.
28. In a casting device, the combination of a movable mold member, a stationary stop, means on the mold member for engaging said stop, levers connected with said means, and means for releasing the casting when the first named member moves into engagement with said stop.
29. In a casting device, the combination of a movable mold member, a stop, an end segment for the mold member movable therewith, and means for forcing said segment away from the mold member when said member moves into position to engage said stop.
30. In a casting device, the combination of a movable end segment, an ejecting device, and means for simultaneously moving the end segment away from the casting and operating the ejecting device.
31. In a casting device, the combination of a movable mold wall, an ejecting device comprising rollers for supporting the casting, and a means for operating the movable mold wall and ejecting device.
32. In a casting device, the combination

of a movable mold member, a set of rollers carried thereby, and means for moving said rollers into a position to engage the casting carried by the mold member from below 5 when the mold member moves into a certain position, whereby the casting will be supported on said rollers.

33. In a casting device, the combination of a movable mold member, a set of rollers carried thereby, a stationary stop, and means adapted to be operated for engaging said stop for moving said rollers into position to engage the casting from below and lifting it from said mold member.

34. In a casting device, the combination of a movable mold member, rollers thereon, a stationary stop, means connected with the rollers for moving them into position to eject the casting from the mold member when the 20 member moves into engagement with the stop, and means for moving said mold member into an inclined position.

35. A casting device comprising a movable mold member having rollers thereon in 25 position to support the casting.

36. A casting mold having bodily movable rollers in position to support the casting.

37. A casting mold having an anti-friction device in position to support the casting in 30 inclined position.

38. A casting device comprising a movable mold member adapted to carry the casting with it and anti-friction rollers on said member for supporting the casting.

39. In a casting device, the combination of a movable mold member, rollers carried thereby, a delivery table, and means on the delivery table for moving said rollers into a position to eject the casting from the mold 35 member.

40. In a casting device, the combination of a movable mold member, a delivery table

having a stop and rollers arranged therein in an inclined position, means for moving said mold member into position to engage said 45 stop, and rollers on said mold member adapted to eject the casting and support it in inclined position whereby the casting may descend by gravity on the delivery frame.

41. In a casting device, the combination of a mold member having rollers thereon in position to support the casting, with a delivery table having rollers in inclined position for receiving the casting from the mold member.

42. In a casting device, the combination of a mold member having rollers thereon in inclined position in position to support the casting, with a delivery table having rollers for receiving the casting from the mold member.

43. In a casting device, the combination of a mold-member having rollers thereon in position to support the casting, with a delivery table having rollers thereon in line with the rollers on the mold member when the mold is in delivering position for receiving the casting from the mold member.

44. In a casting device, the combination of a mold-member having rollers thereon in 70 inclined position when the mold member is in position for delivering the casting, with a delivery table having rollers thereon in inclined position and in line with the rollers of the mold-member for receiving the casting 75 therefrom.

In testimony whereof I have hereunto set my hand, in the presence of two subscribing witnesses.

H. A. WISE WOOD.
